UNITED STATES PATENT OFFICE

JOSEPH D. McNUTT, OF NEW HAVEN, CONNECTICUT, ASSIGNOR, BY MESNE ASSIGNMENTS, TO WINCHESTER REPEATING ARMS CO., OF NEW HAVEN, CONNECTICUT, A CORPORATION OF DELAWARE

PRIMING MIXTURE

No Drawing.

Application filed March 23, 1927. Serial No. 177,842.

My invention relates to an improvement in priming mixtures, the object being to produce a priming mixture of such a character that it will leave no corrosive residuum to act on 5 the material of the barrel of the firearm in which it is used, and which will not deteriorate in storage.

With these ends in view, my invention consists in a priming mixture comprising a 10 metallic nitrate, a metallic thiocyanate, a metallic fulminate, and a chemically-basic stabilizing agent.

In carrying out my invention, I employ the 15 above-named ingredients in substantially the following proportions, dependent upon the specific use to be made of the mixture:

485 parts of mercury fulminate, carrying 16% of water;
209 parts of barium nitrate;
20 76 parts of lead thiocyanate;
230 parts of ground glass, and
From $\frac{1}{2}$ to 2 parts of diphenylamin.

In proceeding to make the mixture, the 25 diphenylamin or other chemically-basic stabilizer and the barium nitrate are treated with a sufficient quantity of alcohol to effect their intimate mixture, which is then evaporated to dryness. The barium nitrate and the stabilizing agent are thus brought into the most intimate relations. The required quantity of 30 barium nitrate and stabilizer so mixed, is then weighed out, together with the required quantities of lead thiocyanate and ground glass, and these are mixed in any convenient 35 manner. A small amount of a solution of gum in water is now incorporated with the mixture; the required quantity of mercury fulminate is added thereto; and the whole is thoroughly mixed together. The resultant 40 mixture is then ready for immediate use in the manufacture of primers or of primed rim-fire cartridge shells.

Most priming compositions of the prior 45 art depend upon some salt of chloric acid, such as potassium chlorate, in combination with a fuel mixture containing unoxidized sulphur or carbon. Such priming mixtures, although otherwise excellent, have the serious defect of leaving a residue containing metallic chlorides deposited in the bore of the arm in which

they are used. Such salts, when moist, have a highly corrosive action on most ferrous alloys and being strongly hygroscopic, attract moisture from the air and exert a ruinous effect upon the gun barrel in which they have been deposited, which it is very difficult to obviate or counteract.

Many attempts have been made in the past to use priming mixtures dependent upon the 55 properties of mercury fulminate, together with derivatives of nitric acid, but have failed of complete success, owing to either the extreme brisance of this compound, or to its instability. Upon standing the metallic salts of fulminic acid, in the presence of certain nitrates, decompose, very gradually at first. But owing to the acid nature of the decomposition products this is a self-accelerating 60 process, unless the said products be nullified 65 as fast as formed.

I have discovered that a variety of substances may be used to destroy or render 70 harmless these decomposition products, such substances being decidedly basic in character, 75 typical examples being carbonates of strongly basic radicals, such as ammonia, the alkali metals or the alkaline earth metals. Such substances are defined in the claims as "chemically-basic stabilizing ingredients". I 80 prefer, however, to use basic organic compounds, as these are less likely to leave any solid residues after the explosion of the mixture. In particular, I find the substituted 85 ammonia compounds to accomplish the desired results. I have described the use of diphenylamin, as this compound has physical characteristics rendering it peculiarly advantageous. I do not, however, limit myself to this compound alone for the purpose of 90 stabilizing the mixture.

In order to mask or cushion the extreme 95 brisance of the fulminate, I combine with it an oxidizing compound and a fuel, thus lessening the amount of fulminate required, by increasing the amount of flame, the burning 100 time and the resultant temperature. I avoid, of course, compounds containing chlorine or any substantial amount of alkali metals, in order that the residues may be free from hygroscopic and corrosive elements. In the

specific example given, I use barium nitrate as an oxidizing agent and lead thiocyanate as a fuel. The ground glass is merely a regulator of the sensitivity of the mixture to mechanical shock, and may be omitted entirely, or increased in quantity to meet varying requirements.

I claim:

- 10 1. A priming mixture, comprising a metallic fulminate, an oxidizing agent having a non-corrosive residue, a fuel having a non-corrosive residue and diphenylamin.
- 15 2. A priming mixture, comprising a heavy metal fulminate, an alkaline earth metal nitrate, a heavy metal thiocyanate and diphenylamin.
- 20 3. A priming mixture, comprising mercury fulminate, barium nitrate, lead thiocyanate and diphenylamin.
- 25 4. A priming mixture, comprising substantially 485 parts of mercury fulminate, substantially 209 parts of barium nitrate, substantially 76 parts of lead thiocyanate, and up to two parts of diphenylamin.
- 30 5. A priming mixture, comprising substantially 485 parts of mercury fulminate, substantially 209 parts of barium nitrate, substantially 76 parts of lead thiocyanate, substantially 230 parts of ground glass and up to two parts of diphenylamin.
- 35 6. A priming mixture, comprising substantially 485 parts of mercury fulminate, substantially 209 parts of barium nitrate, substantially 76 parts of lead thiocyanate, substantially 230 parts of ground glass, up to two parts of diphenylamin, and substantially 8 parts of gum.

In testimony whereof, I have signed this specification.

JOSEPH D. McNUTT.
